ILLUMINABLE DECORATIVE DEVICE

Leonard B. Johnson, Smethport, Pa.

Application March 13, 1953, Serial No. 24,020

Term of patent 14 years

(Cl. D48—20)

To all whom it may concern:

Be it known that I, Leonard B. Johnson, a citizen of the United States, residing at Smethport, in the county of McKean and State of Pennsylvania, have invented a new, original, and ornamental Design for an Illuminable Decorative Device, of which the following is a specification, reference being had to the accompanying drawing, forming part thereof.

Figure 1 is a front elevational view of an illuminable decorative device, showing my new design;

Figure 2 is a side elevational view thereof; and
Figure 3 is a top plan view.

The dominant features of my design are shown in solid lines.

I claim:

The ornamental design for an illuminable decorative device as shown and described.

LEONARD B. JOHNSON.
